UNITED STATES PATENT OFFICE

2,549,228

KEY HOLDER

Dezelle Ostrander, South San Francisco, Calif.

Application January 30, 1948, Serial No. 5,313

1 Claim. (Cl. 70—458)

1

The present invention relates to key holder, tag and container and it consists in the combinations, constructions and arrangements of parts herein described and claimed.

It is an object of the present invention to provide a key holder having a body formed of a single piece of material and providing novel means for attaching an identification tag or the like thereto and which is adapted to contain a key therein when the same is not in use.

A further object of the invention is the provision in a device of the character set forth of novel means for latching a key therein.

A further object of the invention is to the provision of several novel means for attaching the holder to a key chain or the like.

A further object of the invention is the provision of a key container which is adapted to protect the clothing of the user from the rough edges of a key contained therein.

Another object of the invention is the provision of a device of the character set forth above which is extremely simple in its construction and operation and yet which is effective and efficient in use.

Other and further objects of the invention will become apparent from a reading of the following specification taken in conjunction with the drawings, in which:

Figure 1 is a front elevational view of an embodiment of the invention.

Figure 2 is a side elevational view of Figure 1.

Figure 3 is a rear elevational view of the device shown in Figure 2.

Figure 4 is a sectional view taken along line 4—4 of Figure 1.

Figure 5 is a sectional view taken along line 5—5 of Figure 4.

Figure 6 is a plan view of a blank forming a part of the present invention.

Figure 7 is a front elevational view of a modified form of the invention.

Figure 8 is a sectional view taken along line 8—8 of Figure 7.

Figure 9 is a rear elevational view of the device shown in Figure 7.

Figure 10 is a sectional view taken along line 10—10 of Figure 8.

Figure 11 is a plan view of a blank forming a part of the invention shown in Figures 7 to 10, inclusive, and

Figure 12 is a side elevational view of the blank shown in Figure 11 after certain operations have been performed thereon.

Generally, there is provided a key container in

2

which one form of the invention consists of an elongated blank adapted to have its side edges bent inwardly after which the same is folded at approximately its center whereby to provide on either side of the finished device a slot for the reception of identification cards or the like. One end of the blank has integrally formed therewith a tongue which is adapted to protrude through an opening formed adjacent the other end. A second opening is provided for the reception of the outer end of the tongue. A novel arrangement is provided for the reception of an inner end of a swiveled member for the attaching of a key chain or the like. The folded device has means for pivotally mounting a key so that it normally lies within the device but which may be easily rotated outwardly for use. In a modification of the invention a removable eye is utilized for attaching the device to a key chain or the like and only one side of the folded container is provided with grooves for the reception of identifying cards.

Referring more particularly to the drawings, there is shown therein, in Figures 1 to 6, inclusive, an elongated blank 10 having at either side an outwardly extending wing 11 and having a circular opening 12 adjacent one end adjacent to which upon its inner side is provided a slot 13. The other end of the blank is provided with an outwardly extending integrally formed tongue 14. A circular opening 15 is provided between the ends of the blank and its center is slightly to the left of a center line 16, as viewed in Figure 6 of the drawing.

In preparing the blank 10 for use, the wings 11 are folded inwardly and thereafter the blank is folded along the center line 16. Folding the wings 11 inwardly provides flanges 17 for the reception of identification cards 18 and 19. Alternatively, mere colored cards may be used, a different color being used for each container so that the user may readily identify his various keys by the colored cards rather than being put to the necessity of reading data which may be placed upon such cards.

A swiveled connector is provided with an eye 20 to which is affixed a shank 21 the inner end of which is provided with a head 22. The opening 15 is of a size to exactly receive the head 22 when the blank 10 is in flattened condition and it is so inserted prior to the folding of the blank after which the opening 15 is contracted about the shank 21 to lock the head 22 therein.

In use, after the head 22 has been inserted into the opening 15 and the flanges properly formed

and the blank folded in the manner above set forth, a key 23 may be placed in the device by inserting the tongue 14 through the conventional opening 24 in the key 23 thereafter inserting the tongue in the opening 12 after which the same is bent in a direction toward the fold and inserted into the slot 13. The identification cards 18 and 19 may then be placed between the flanges 17 and thereafter, if desired, a piece of clear plastic may be placed over both the card 18 and the tongue 14. It will be seen that the key 23 may now rotate a full 360 degrees and that normally the teeth 25 of the key will lie within the container but that the key may be quickly and easily rotated about the tongue 14 to operable position.

In the form of the invention shown in Figures 7 to 12, inclusive, there is provided an elongated body divided by a transversely extending center line 30 into a section 31 and a section 32. The section 31 is provided with outwardly extending elongated integrally formed wings 33 and a pair of slots 34 and 35 adjacent the outer end thereof. A pair of openings 36 and 37 are formed on either side of the center line 30 and the outer end of the section 32 is provided with an outwardly extending integrally formed tongue 38.

In this form of the invention the area of the blank adjacent the center line 30 is folded to form a loop 39 and wings 33 are folded inwardly to form flanges 40 for the reception of an identification card 41.

A spring clip is bent to form an eye 42 for attachment to a key chain or the like and has its extremities bent inwardly, as indicated at 43, so that the ends may engage the looped portion 39.

In the operation of this form of the invention a key 44 may be mounted in the device by inserting the tongue 38 into the conventional opening 45 in the key and thence passing the same through the slot 34 and thence into the slot 35.

The operation of the device is similar to that above described, with regard to Figures 1 to 6, inclusive, and it will be understood that a piece of clear plastic material may be placed over the identification card 41 also as above described. The openings 36 and 37 may be utilized to attach the device to the conventional key ring.

While only certain forms of the invention have been shown and described herein, it will be readily apparent to those skilled in the art that many minor modifications may be made without departing from the spirit of the invention or the scope of the appended claim.

What is claimed is:

15 A device of the character described comprising a U-shaped member having a pair of openings adjacent the end of one leg thereof, and a bendable tongue formed integrally with the end of the other leg thereof and adapted to pass through an opening in a key and laced through said pair of adjacent openings to secure the same whereby a key may be pivotally mounted on said U-shaped member.

DEZELLE OSTRANDER.
